UNITED STATES PATENT OFFICE.

ROLAND B. DALEY, OF CHICAGO, ILLINOIS.

PHONOGRAPH TONE ARM.

Application filed June 5, 1922. Serial No. 565,949.

To all whom it may concern:

Be it known that I, ROLAND B. DALEY, a citizen of the United States, and resident of Chicago, in the county of Cook and State of Illinois, have invented certain new and useful Improvements in Phonograph Tone Arms, of which the following is a full, clear, concise, and exact description, reference being had to the accompanying drawings, forming a part of this specification.

This invention relates to phonograph apparatus, and particularly to the tone arm and the sound exit stem from the reproducer, and the manner of joining it to the tone arm.

The object of the invention is to provide a simplified type of universal tone arm for playing the different types of records with the needle and reproducer in the correct position in each case, and also to provide a sound passage through the reproducer exit stem and tone arm from which will be eliminated, so far as possible, all abrupt turns.

One of the features of the present invention is the provision of a tone arm which consists of two telescopically and rotatably connected parts, one of which connects directly with the reproducer exit, thereby eliminating the usual connecting tube.

Another feature of the invention resides in the arrangement of the sound exit stem so that the axis of the sound exit channel of the reproducer extends at a relatively sharp acute angle to the plane of the reproducer diaphragm.

Another feature resides in the construction which permits the placing of the reproducer needle at substantially the same angle to the record whether it is being used with a lateral cut record or a hill and dale record, and in which, in both instances, the point of the needle is at substantially the same distance from the axis of rotation of the tone arm elbow.

Another feature resides in the arrangement which, in addition to the features above set forth, provides that when the reproducer is arranged to play lateral cut records, the plane of the diaphragm intersects the tone arm elbow at substantially its axis of rotation, and when arranged for use with hill and dale type records, the plane passing through the axis of the needle socket at right angles to the diaphragm intersects

the tone arm elbow at substantially its axis of rotation.

Other features and advantages will appear from time to time as the description of the invention progresses.

Referring now to the drawings which show the preferred embodiments of applicant's invention,

Figure 1 is a plan view of the tone arm partly in section, and the reproducer in a position to play lateral cut records;

Figure 2 is a side elevation of the arrangement of Figure 1.

In both Figures 1 and 2, the reproducer is shown in its needle changing position in dotted lines;

Figure 3 is a plan view of the device of Figures 1 and 2, but showing the reproducer in a position for playing hill and dale records;

Figure 4 is a side elevation of the device of Figure 3;

Figure 5 is a plan view of a modified form of tone arm;

Figure 6 is a side elevation of the tone arm of Figure 5;

Figure 7 is a section on the line 7—7 of Figure 5, and

Figure 8 is a section on the line 8—8 of Figure 5.

It is thought that this invention will be best understood by a detailed description thereof taken in connection with the drawings.

Referring now to the drawings, in which like reference characters in the several views indicate like parts, at 20 is shown the vertically extending portion of the tone arm elbow which has integral therewith the laterally extending portion 21. The portion 21 is provided with the internal annular recess 22 within which is received the reduced end portion 23 of the tone arm extension member 24. The connection between the parts 21 and 23 is such that the tone arm extension 24 may be readily rotated with respect to the tone arm elbow member 21. Any desired or appropriate means may be provided for limiting the rotary movement of the part 23 within the recess 22, and for providing a substantially constant frictional engagement between the two parts. Suitable means for this purpose will be subsequently described in connection with the modification shown in Figures 5 and 6.

The tone arm extension 24 terminates at one end in a portion 25, the axis of which extends at an oblique angle to the axis of the member 24. The reproducer shell 26 has an exit stem 27 provided with a reduced portion 28 telescopically received within the angularly extending portion 25 of the tone arm extension. It will be noted that the axis of the sound exit channel 29, and also the axis of the stem 27, is arranged at an acute angle to the plane of the reproducer diaphragm. This angle is preferably substantially 40°.

This invention does not relate to the diaphragm, needle support, or any of the moving parts associated with the reproducer shell. Any desired or approved type of this mechanism may be employed.

The exit stem 27 is rotatable with regard to the tone arm extension, and any suitable or desired means may be provided to limit the relative rotation of these parts, one to the other, or to provide constant frictional engagement between the two. Suitable means for this purpose will be subsequently described.

In Figures 1 and 2, the reproducer is shown in solid lines in a position for playing lateral cut records. In this position, it will be noted that the plane of the diaphragm passes through the axis of rotation of the vertically extending portion 20 of the tone arm elbow. It will also be noted by reference to Figure 2, that the needle socket 30 and needle 31 are arranged at an angle of approximately 55° to the surface of the record 32. It is desirable to have the axis of the reproducer exit channel substantially intersect the axis of the diaphragm and the axis of the needle and needle socket. In other words, the axis of the exit channel, the axis of the needle socket and the axis of the diaphragm should all pass substantially through a common point.

It will be seen by reference to Figures 1, 2 and 3, that the axis of the tone exit channel 29 passes through the plane of the diaphragm at substantially the point where the stylus bar 33 is attached to the diaphragm 34.

It will also be noted from an inspection of Figure 1 of the drawings, that the vertical plane passing through the axis of the exit channel 29 passes much nearer to the needle point than would be the case if the exit channel extended at an angle of substantially 90° to the plane of the diaphragm. Thus the turning movement of the force exerted on the needle point by the record will be less, and the danger of displacement of the reproducer and chattering thereof is materially reduced.

The needle changing position of the reproducer and needle is shown in dotted lines in Figures 1 and 2. The reproducer is placed

in needle changing position by rotating the stem 27 with relation to the tone arm extension 24. It will be noted that when the reproducer is in needle changing position, it lies at an angle of substantially 90° with regard to its playing position. Also, it will be noted that the needle, when the reproducer is in changing position, lies immediately over the position it occupies when in playing position. When in needle changing position, the needle will point upwardly and outwardly, thus making it exceedingly convenient to change the needle.

The reproducer is shown in a position to play hill and dale records in Figures 3 and 4. The change from the position of Figures 1 and 2 to that of Figures 3 and 4 is accomplished by first rotating the reproducer to the needle changing position, as above described, and then rotating the extension arm 24 substantially 180° in relation to the tone arm elbow. The character of the sound passage through the tone arm is in no wise altered by the change of the reproducer from a position to play lateral cut records to a position to play hill and dale records.

In applicant's device, only one movement, in addition to moving the reproducer to needle changing position, is necessary in changing the reproducer from a position to play lateral cut records to a position to play hill and dale records, or vice versa. In any instance, it is necessary to move the reproducer to needle changing position in order to change the needle. Having moved the reproducer to needle changing position, but one movement is necessary, a rotary movement of the tone arm extension, in order to place the reproducer in a position to play the other type of record. As a matter of fact, assuming that one uses the type of needle which must be changed after each record is played, no more movement is necessary to insert a new needle. Thus, the number of movements required to change the reproducer from a position to play one type of record to the position to play the other type is reduced to the minimum.

When the reproducer has been changed to play hill and dale records, the needle is arranged at substantially the same angle to the record as when used in playing lateral cut records, namely, substantially 55°, and is positioned the same distance from the axis of rotation of the tone arm elbow. Also, it will be noted from Figure 3 that a plane at right angles to the diaphragm and passing through the needle socket intersects the axis of rotation of the tone arm elbow. This feature of having the plane of the diaphragm pass through the axis of rotation of the tone arm when arranged to play lateral cut records, and of being so positioned, when arranged to play hill and dale records, that a plane at right angles to the diaphragm

through the needle socket passes through the axis of rotation of the tone arm, is very desirable.

It is also exceedingly desirable that the needle should be positioned the same distance from the axis of rotation of the tone arm elbow when playing one kind of record as when playing the other, as by this arrangement the needle may be caused to engage the record approximately along the radius of the record which extends at approximately right angles to a line joining the axis of rotation of the tone arm to the needle. In other words, the plane of the diaphragm of the reproducer in Figures 1 and 2 will be positioned substantially tangential to the record groove, and the plane at right angles to the reproducer diaphragm passing through the needle socket will be substantially tangential to the record groove when arranged as in Figures 3 and 4. Of course, due to the arc which the needle travels in its movement from the outer edge of the record toward the center, this tangential arrangement is not true for all positions but may be approximated for all positions.

The modification shown in Figures 5 and 6 is very similar to that shown in Figures 1 to 4, the only difference being that the tone arm elbow has its laterally extending portion 35 arranged at an angle of less than 90° to the vertically extending portion 36. Also, the angularly extending portion 37 of the tone arm extension 38 is arranged at a slightly different angle to the tone arm extension than are the similar parts in Figures 1 to 4. The operation and results obtained by the structure of Figures 5 and 6 is very similar to that above described. However, in changing from a position to play lateral cut records to a position to play hill and dale records, the tone arm extension need not be rotated through so great an angle. It will be recalled that the tone arm extension 24 was rotated substantially 180° in the change from a position to play lateral cut records to a position to play hill and dale records. In the arrangement of Figures 5 and 6, the tone arm extension need be rotated only about 120°. The arrangement of the extension 37 and the reproducer stem 39 is also slightly different in that the extension 37, when in a position to play lateral cut records, inclines slightly upwardly, and the reproducer stem 39 inclines slightly downwardly so that the axes of the sound passage through the part 37 and through the part 39 are coincident.

It will be understood that the extension member 38 is telescopically received by the member 35, and that the reproducer stem 39 is telescopically received by the angularly extending member 37 in the same manner as has been described in connection with Figure 1.

The details of the telescopic arrangement between the parts of Figure 5 are shown in Figures 7 and 8. In Figure 8, 40 indicates the reduced portion of the extension member 38 which is received within the end of the member 35. If desired, the portion 40 may be provided with a circumferential groove 41 into which projects a screw 42 inserted through the member 35. This arrangement acts to prevent the tone arm extension being withdrawn from the elbow, and also acts to limit the rotary movement of one relative to the other. In order that the frictional engagement of these parts may be maintained substantially constant and take up the wear which occurs, the member 40 may be provided with a groove 43 within which is placed a flat spring 44 formed as the arc of a circle somewhat smaller than the inner circumference of the member 35.

In Figure 7 is shown the nature of the connection between the parts 39 and 37. The reduced portion 45 of the part 39 may be provided with a circumferential groove 46 into which may project a screw 47 carried by the part 37. At 48 is indicated a bowed flat spring positioned in a longitudinally extending slot in the part 45 which acts to produce constant frictional engagement of the telescoping parts. This arrangement of Figures 7 and 8 may advantageously be applied to the structures of Figures 1 to 4, although any other suitable means may be substituted therefor.

As is usual, the tone arm elbow 36 is so supported as to be rotatable about its vertical axis and also to permit the extension 35 to move vertically to permit the needle to be placed on or removed from the record, and also to permit the needle to maintain a constant engagement with the record while the record moves slightly up and down during its rotary movement, as is usual. The details of the supporting means for the tone arm elbow are not shown, and any of the well known supporting arrangements may be employed.

The preferred embodiment of applicant's tone arm and one modification have been described above. Many other modifications are possible, but these several modifications all consist merely in varying the angles between the vertically extending portion of the tone arm elbow and the forwardly extending portion, changing the angle of the turn in the tone arm extension and slightly changing the angle of the axis of the tone exit channel to the diaphragm. Applicant contemplates other modifications than those set forth above, and it is, therefore, to be understood that the invention is to be limited merely by the scope of the appended claims. Having now described my invention, what I claim is new and desire to secure by Letters Patent of the United States is:

1. In a phonograph, a reproducer having a sound exit stem extending at an acute angle to the plane of the diaphragm of the reproducer, a tone arm elbow, and an extension to the elbow, one end of which communicates with and is rotatable with respect to said elbow, the other end of which communicates with and is rotatable with respect to the exit stem of the reproducer.
2. In a phonograph, the combination with a reproducer having a sound exit tube, the axis of which extends at an acute angle to the plane of the diaphragm of the reproducer and passes through a point located substantially on the axis of the needle socket, of a tone arm having an elbow, and an extension tube, one end of which is rotatably connected to said elbow, and the other end of which is rotatably connected with said exit tube.
3. In a phonograph, the combination with a reproducer having a sound exit tube, the axis of which extends at an acute angle to the plane of the diaphragm of the reproducer and passes through approximately the center of the diaphragm and the axis of the needle socket, of a tone arm elbow, and an extension tube, one end of which is rotatably connected to said elbow, and the other end of which is angularly displaced and rotatably connected with said exit tube.
4. In a phonograph, the combination with a reproducer having a sound exit stem extending at an acute angle to the plane of the diaphragm, of a tone arm elbow, and an extension having an angularly extending end, said extension having one end rotatably connected with the sound exit stem, and having the other end rotatably connected with one arm of said elbow.
5. In a phonograph, the combination with a reproducer having a sound exit stem extending at an acute angle to the plane of the diaphragm, of a tone arm elbow, and an extension having one end rotatably connected with said elbow, and the other end angularly displaced and rotatably connected with the reproducer exit stem, being arranged to be substantially parallel to the plane of the record when in playing position.
6. In a phonograph, the combination with a reproducer having a sound exit stem extending at an angle to the plane of the reproducer diaphragm, of a tone arm including an extension tube, one end of which is angularly displaced and is so connected with the sound exit stem as to permit said reproducer to be rotated relative to said tube, and a tone arm elbow having one arm rotatably connected to the opposite end of said extension tube, the parts being so arranged and proportioned that by the combination of two movements, one a rotation of the reproducer stem relative to said extension, and the other a rotation of the extension relative to said elbow, the reproducer may be changed from a position where the diaphragm of the reproducer is perpendicular to the record and its stylus bar inclined at an angle to the record to a position where both the diaphragm and the stylus bar are inclined to the record at substantially the angle of the stylus bar in the previously described position.
7. In a phonograph, a reproducer having a sound exit stem, a tone arm elbow, and a tone arm extension, said tone arm extension being telescopically and rotatably connected at one end to one arm of said elbow, and at the other end to said exit stem, said parts being so arranged and proportioned that the rotatable adjustment of said reproducer with relation to said extension, and of said extension with relation to said elbow, will change the reproducer from a position in which the diaphragm of the reproducer is perpendicular to the record and its stylus bar inclined at an angle thereto to a position in which both the diaphragm and stylus bar are inclined to the record at an angle substantially the same as the angle of the stylus bar to the record in the first described position and the needle point is positioned from the axis of rotation of the tone arm a distance substantially the same as in the first described position.
8. In a phonograph, the combination with a reproducer, of a tone arm including an elbow which is rotatable horizontally about a vertical axis, and an extension to said tone arm, one end of which is rotatably connected to one arm of said elbow, the other end being rotatably connected to the exit stem of the reproducer, the parts being so proportioned and arranged that rotative movement at opposite ends of the extension may shift the position of the reproducer from one playing position to another playing position in which the plane of the reproducer lies at substantially right angles to the plane occupied in the first mentioned position, the distance from the vertical axis of the elbow to the needle in the reproducer being approximately the same in both playing positions.
- In witness whereof, I hereunto subscribe my name this 29th day of May, 1922.
